DESIGN FOR A BUFFET OR SIMILAR ARTICLE

William J. Hickerson, Philadelphia, Pa.

Application June 13, 1938, Serial No. 77,798

Term of patent 3½ years

To all whom it may concern:

Be it known that I, William J. Hickerson, a citizen of the United States of America, residing at Philadelphia, in the county of Philadelphia and State of Pennsylvania, have invented a new, original, and ornamental Design for a Buffet or Similar Article, of which the following is a specification, reference being had to the accompanying drawing, forming part thereof, in which:—

Fig. 1 is a view in front perspective of a buffet or similar article showing my new design.

Fig. 2 is a side elevation of Fig. 1.

I claim:

The ornamental design for a buffet or similar article, as shown.

WILLIAM J. HICKERSON.
